United States Patent Office.

CHARLES G. MORTIMER, OF NEW YORK, N. Y.

Design No. 4,037, dated May 17, 1870.

DESIGN FOR A HAND-STAMP.

The Schedule referred to in these Letters Patent and making part of the same

To all whom it may concern:

Be it known that I, CHARLES G. MORTIMER, of the city and State of New York, have invented and made a new and original Design in Stamps for Marking Clothing, &c., and the following is declared to be a correct description of the same.

In the drawing—

a is the bed carrying the ears *b b* and fulcrum-pin *c* of the swinging arm *d*, at the end of which is the type-holder *e* and knob or handle *f*.

g is a spring to raise up the arm *d* and stamp.

What I claim, and desire to secure Letters Patent for, is—

An improved design for stamps for marking clothing, &c., as clearly shown in accompanying drawing.

In witness whereof I have hereunto set my signature this 30th day of April, 1870.

CHARLES G. MORTIMER.
